A CORPORATION OF DELAWARE

SYSTEM FOR PARALLEL OPERATION OF ALTERNATORS

Application filed February 16, 1925. Serial No. 9,537.

This invention concerns the operation of high frequency alternators in parallel providing means for obtaining a large synchronizing torque and avoiding to a large extent the tendency of the alternators to hunt. The arrangement has been found particularly useful in the parallel operation of alternators of the type shown in the U. S. patents to Alexanderson 1,008,577, 1,110,029 and 1,110,030 but is, of course, not limited to the particular case of alternators of this type.

One object of the invention is to provide a system for operating alternators in parallel providing for a large synchronizing torque.

Another object of the invention is to provide a system for parallel operation of alternators whereby hunting is reduced to a large extent.

Another object of the invention is to provide an arrangement for the parallel operation of alternators providing a large synchronizing torque and tending to dampen hunting oscillations quickly.

Still another object of the invention is to provide an arrangement for the operation of alternators in parallel whereby during hunting oscillations the synchronizing torque will be increased as the phase angle between the alternators increases and will be reduced as the phase angle between the alternators decreases.

Still another object of the invention is to provide a system for the operation of alternators in parallel whereby the synchronizing torque tending to hold the alternators in phase during hunting oscillations will be greater than the synchronizing torque tending to bring them back into phase.

Still another object of the invention is to provide an impedance in the circulating circuits of alternators operating in parallel and to provide for short circuiting the impedance as the alternators reach maximum out of phase position during hunting oscillations.

In many high power radio communication stations it is very desirable to operate a plurality of high frequency alternators in parallel. The alternators in use for this

purpose have a frequency of from 15,000 to 50,000 cycles per second. This high frequency in itself does not present any special problems in parallel operation but the machines used in such installations have a very high internal reactance and resistance and these features do introduce special problems in the parallel operation. The high internal reactance cuts down the circulating current and therefore the synchronizing torque considerably and it is, therefore, necessary to provide means for neutralizing this reactance. This is done under the present arrangement by placing a condenser of the proper rating in series with each alternator ahead of its paralleling connection. Without such condensers the circulating current would attain a maximum of only 35 percent of full load current and a power interchange of only about 10 percent of full load power at the most critical phase angle. When the condensers are used and adjustment is made for the highest possible power interchange its value at the most critical phase angle is about twice full load power. This is, of course, not a practical condition since practically the whole power output of the machines would be absorbed in the internal resistance of the machines themselves but by properly dimensioning the condensers the power interchange can be made of the desired value. The preferred arrangement is to provide for a power interchange of about 25 percent of the full load power.

When such high frequency alternators are operated in parallel there is a decided tendency for hunting between them as is the case under certain conditions with synchronous machines at power frequencies. There seem to be many conditions which tend to produce hunting in the case of high frequency alternators under telegraphic load and they seem to vary with the individual installations and even to change frequently in the same installation. The latter is probably due to certain variations in the power supply such as might be caused by the changing of generator units, etc.

One cause for hunting seems to originate in the driving motors and is probably due

to certain torque harmonics which do not coincide in the two motors.

A second source of variations causing hunting is found in the telegraphic keying. 5 The keying is usually controlled automatically so that the impulses recur with great regularity. Since the motor input and the alternator output cannot be exactly balanced under both conditions of load a tendency to hunt is produced and when the keying speed corresponds to the period of the hunting between the alternators the hunting will tend to build up and the alternators would drop out of step if no corrective measures were taken.

10 Similarly any initial hunting would tend to increase under favorable conditions of keying due to the fact that the synchronizing torque is not the same with the key open as with the key closed either with or without the antenna load. On account of this the torque drawing the machines back into step might be greater each time than that restraining them from going out of step in the 15 opposite direction, thus causing an increase in hunting.

10 A third source of hunting is found in any irregularity of the alternators themselves due to inexact spacing of the poles in the 20 rotor or to an irregularity in the field flux that the rotor passes through. Such irregularities cannot be entirely eliminated in machines with such a large number of poles as are required to produce these high frequencies. Thus the load may vary with 25 rotor position and hunting may result if the hunting period corresponds to the alternator revolutions.

It has been found that in such installations, even when all reasonable means are 40 taken to keep the alternators in step, the conditions of hunting are very serious. The usual methods of preventing hunting in synchronous machines of power frequency 45 are impractical because the mean power interchange between two such high frequency alternators is practically zero when they are properly balanced. According to the present invention an inductance is placed in the circuit connecting the two 50 alternators which under certain conditions will be short circuited. The value of the condensers referred to above is such that with this inductance short circuited the power interchange between the two alternators at the most critical phase angle is 55 about 25 percent of the full load power of either machine, while with the inductance in circuit it is about half this value. A 60 relay is provided for short circuiting this inductance which is controlled in such a way that it will short circuit the inductance while no hunting is taking place and during hunting while the phase angle between the 65 alternators is increasing, thus getting the

higher value of synchronizing torque. But when the phase angle is decreasing the relay will open the short circuit and place the inductance in the circulating circuit thus giving the lower value of torque until the 70 alternators reach their in-phase position at which time the inductance will again be short circuited. This has the effect of dampening out the hunting very rapidly.

The invention can best be understood from 75 the following detailed description which should be read in connection with the accompanying drawings, in which

Fig. 1 is a schematic representation of an arrangement conforming to the invention by 80 which the synchronizing torque of alternators operating in parallel may be increased,

Fig. 2 is a schematic arrangement by 85 which the hunting oscillations of alternators operating in parallel may be quickly damped,

Fig. 3 is a diagram of a complete circuit arrangement for the operation of alternators in parallel according to the invention, and

Fig. 4 is a group of comparative curves 90 illustrating the operation of the device for dampening out hunting oscillations.

Referring now to Fig. 1, in which is 95 shown a very simple schematic arrangement for increasing the synchronizing torque between alternators operating in parallel, A_1 and A_2 represent two alternators in parallel having internal inductances represented by L_1 and L_2 . This inductance, in machines of the type under discussion, is ordinarily 100 large enough to cut down the circulating current and therefore the synchronizing torque considerably below the value necessary to keep the alternators in step. The effect of this internal inductance is neutralized by inserting the condensers C_1 and C_2 in series with the alternators, thereby correcting the power factor in the circulating circuit L_1 , C_1 , C_2 , L_2 and causing a larger 105 circulating current to flow. By correctly 110 dimensioning the condensers C_1 and C_2 this circulating current may be adjusted to the desired value.

Fig. 2 illustrates the method of dampening hunting oscillations in alternators operating in parallel. For the sake of clearness all circuits and devices have been omitted from this figure except the circulating circuit and the device S and circuits necessary to dampen the hunting oscillations. A 115 and A_2 represent alternators operating in parallel and cross connected through the circuit A_1 , conductor 138, conductor 139, alternator A_2 , and conductor 140. In the tie comprising the conductors 138 and 139 is 120 placed an inductance 131 which under certain conditions explained hereinafter will be short circuited by the contacts of relay 132. Across the alternators A_1 , A_2 are connected 125 transformers 128 and 129, respective- 130

ly, having their secondaries connected in series so that when the alternators are in phase the voltages in these secondaries will neutralize each other. In circuit with the 5 series connected secondaries are the resistance 136 and the rectifier 130. One terminal of the resistance is connected to the coil of polarized relay 133 to the other terminal of which is connected one plate of the condenser 135. The other plate of this condenser is connected to the opposite terminal of resistance 136.

When hunting begins and the alternators start to get out of phase with each other, 15 the voltages in the secondaries of the transformers 128 and 129 will no longer balance and rectified current will begin to flow through the resistance 136. This current will increase in value as long as the phase 20 angle between the alternators is increasing and likewise the voltage across the resistance will increase. This increasing voltage charges the condenser 135. The polarized relay 133 has its armature slightly biased 25 so that its contacts will remain open as long as there is no voltage across the resistance 136 and as long as the voltage is increasing. When the alternators begin to swing back 30 into phase the voltage across this resistance begins to decrease, the condenser 135 begins to discharge and sends a reverse current through the polarized relay 133 causing it to open its contacts. These contacts will remain open as long as the voltage across 35 resistance 136 is decreasing and therefore as long as the phase angle between the alternators is decreasing. When the phase angle reaches zero and starts to increase in the other direction an increasing current will 40 again flow through the resistance 136 causing condenser 135 to charge and the polarized relay 133 to open its contacts.

The contacts of the relay 133 control a 45 circuit comprising a source of energy B and the relay 132 whose contacts serve to open and close a short circuit across the inductance 131. The relay 132 has its armature so biased that as long as there is no current flowing through the relay coil 50 the contacts will be open but when current flows through the relay coil the contacts will close. The inductance 131, when it is in circuit, serves to cut down the circulating current and therefore the synchronizing 55 torque considerably. When, during hunting oscillations, the phase angle between the alternators is increasing in either direction the voltage across resistance 136 will be increasing, the relay 133 will hold its 60 contacts open, the relay 132 will hold its contacts closed and a heavy circulating current will flow between the alternators. This heavy circulating current will persist until the alternators reach their maximum out 65 of phase position. When the phase angle

between the alternators begins to decrease the voltage across the resistance 136 will decrease and condenser 135 will discharge, thereby causing relay 133 to close its contacts, which in turn will cause the relay 132 70 to open its contacts, thereby removing the short circuit around inductance 131 and inserting the inductance in the circulating circuit. This causes the circulating current and therefore the synchronizing torque to 75 decrease. It will thus be seen that as long as the phase angle between the alternators is increasing a large synchronizing torque will be effective to oppose the change. After the phase angle has reached its maximum and begins to decrease a lessened synchronizing torque will be effective and there will, therefore, be a lessened tendency for the alternator armatures to swing past their 80 mean position.

These effects are clearly indicated in the group of curves shown in Fig. 4 in which A represents the circulating current, B represents the phase relation between the alternators and C represents the position of the 85 relay 132, all plotted against time. It will be noted that as the phase angle increases, that is as the curve B rises, the circulating current represented by A will increase until the phase relation reaches a maximum 90 when, owing to the insertion of the inductance 131 in circuit, the circulating current will suddenly drop from the point P to the point Q. The conditions for the lesser 95 circulating current persist until the generators come in phase at the point C when the relay 132 will again close its contacts, short circuit the inductance 131 and allow the circulating current to increase in the 100 opposite direction to the point P' which represents the maximum out of phase position of the alternators in the other direction. At this point the relay 132 again 105 opens its contacts and inserts the inductance 131 in the circulating circuit and the 110 circulating current is again reduced from the point P' to the point Q'. This action is repeated at each maximum out of phase position and the hunting oscillations quickly die out as indicated by the curve A. 115 Due to imperfect machining of the alternators their respective voltages would not be constant. These voltages if plotted with respect to time would show a pure sine wave and a series of harmonics interposed 120 thereon. These harmonics which are of higher frequency than the hunting frequency of the alternators would cause the armature of the relay 133 to chatter. A condenser 134 is shunted across the relay winding to by-pass these harmonics so that the relay responds only to the differential voltages caused by hunting. Condenser 134 125 also serves as a by-pass for radio frequencies and insures greater output for the rectifier. 130

Fig. 3 shows a complete circuit diagram illustrating the use of the devices illustrated schematically in Figs. 1 and 2 in connection with a standard radio telegraph installation. Certain difficulties in connection with the 5 keying in such a system prevent the use of the simple connections shown in Figs. 1 and 2. The operation of keying essentially reduces the alternator voltage to a very low value when the key is open. It is clear, 10 therefore, that under such circumstances the circulating current and therefore the synchronizing torque would drop to a very small value whenever the key were opened and it would, therefore, be very difficult to 15 keep the alternators in step. To avoid such difficulties the simple arrangements in Figs. 1 and 2 have been modified to some extent as shown in Fig. 3. The principal of their 20 operation, however, remains exactly the same as in the simple devices described above.

In this figure the antenna 3 is fed by means of two alternators 1 and 2 represented diagrammatically as of the Alexander- 25 son type. The armature coils of these alternators feed the primaries of transformers 6 and 7 which are coupled to secondaries 8 and 9 in the two branches of the antenna circuit. The operation of keying which is 30 carried out by means of the key 150 in circuit with a source of power 151 causes portions 10 and 11 of these secondaries to be short circuited intermittently by means of 35 magnetic amplifiers shown diagrammatically at 16 and 17. These amplifiers are of a well known type and consist of iron core inductance coils with saturating coils 45 and 46 controlled by the contacts 18 and 19. 40 As indicated in the drawings when key 150 is open contacts 18 and 19 are in the closed position. With these contacts in closed position the cores of the amplifiers are magnetically saturated, owing to the flow of direct 45 current from the batteries 20 and 21, thus reducing the inductance of the magnetic amplifier coils. In this position the magnetic amplifier together with the condensers 14 and 12 form practically a short circuit 50 across the cores 10 and 11 of the transformer secondaries. When key 150 is closed the contacts 18 and 19 are open the current in the saturated coils 45 and 46 is interrupted the inductance of the amplifier 55 coils rises and the path including the amplifier presents a high impedance to the flow of current from the transformers. The alternators thereupon impress a higher voltage upon the antenna circuit. The difference 60 in the power supplied to the antenna in the key open and the key closed positions permits the radiation of signals from the antenna.

One armature coil in each alternator 65 designated respectively as 22 and 23 is segre-

gated, that is, it is not used in the feeding circuit. These coils through the transformers 28 and 29 operate a phase dampening device similar to that described above. As these coils are not included in the feeding circuit it is obvious that their voltage is independent of the load on the alternators. These same coils may be used for the purpose of regulating the driving motor speed in the manner explained in U. S. patent to 70 Alexander 1,400,847. The secondaries of transformers 28 and 29 are connected through the rectifier 30 with the resistance 36 which have the same functions as the rectifier 130 and the resistance 136 in Fig. 2. Across the resistance 36 are connected in series the polarized relay 33 and the condenser 35, the operation of which is exactly analogous to the relay 133 and the condenser 135 of Fig. 2. The relay 33 is shunted by condenser 34, the purpose of which is the same as the condenser 134 of Fig. 2.

The secondaries of the transformers 8 and 9 are tied together by a circuit comprising conductor 38, condenser 12, conductor 40, inductance 31 with its short circuiting contacts, conductor 41, condenser 13 and conductor 39. The condensers 12 and 13 in this circuit correspond to the condensers C_1 and C_2 in Fig. 1 and their action 90 in increasing synchronizing torque is the same as that explained above in connection with that figure. These condensers also serve as part of the capacity for neutralizing the inductance of the magnetic amplifiers 16 and 17, that is, in the present case the single condenser usually used to neutralize the magnetic amplifier inductance is replaced by the two condensers 12 and 14 connected with the magnetic amplifier 16 and 100 the two condensers 13 and 15 connected with the magnetic amplifier 17. The short circuiting contacts of the inductance 31 are controlled by a biasing spring 42 and a polarized relay 32 whose coil circuit which 105 is composed of a variable resistance 37 and source of power is controlled in turn by a biasing spring 43 and a polarized coil 33 in a manner entirely analogous to the simple device shown in Fig. 2. As long as the machines are exactly in phase the voltages of the transformers 28 and 29 will balance each other and there will be no flow of current through the resistance 36. When hunting 110 oscillations commence the phase angle between the machines begins to vary, the voltages of the transformers 28 and 29 are no longer balanced and rectified current begins to flow through the resistance 36. This rectified current increases in value as the 115 phase angle increases. As long as the voltage drop across the resistance 36 is increasing, due to the increasing current, condenser 35 will be charging and the relay 33 will hold its contacts open, thereby de- 120

energizing the control circuit of relay 32 and permitting the short circuiting contacts across the inductance 31 to remain closed. As long as the phase angle is increasing, 5 therefore, the synchronizing torque will have a large value. The circulating current in this case flows through conductor 38, condenser 12, conductor 40, closed contacts of relay 32, conductor 41, condenser 13 and 10 conductor 39. When the alternators reach their maximum out of phase position and start to swing back into phase the difference in the voltages in transformers 28 and 29 will decrease and the rectified current in 15 resistance 36 and therefore the voltage across this resistance will decrease. Condenser 35 will then discharge through the coil of polarized relay 33 causing it to close its contacts and energize the coil of relay 32. 20 The latter will open its contacts and remove the short circuit around the inductance 31 and the circulating current from which the synchronizing torque results will thereupon have to flow through inductance 31. 25 Its value will, therefore, be reduced and the synchronizing torque will likewise be smaller. This action will be repeated every time the machines leave their out of phase position and reach a maximum, thereby 30 quickly dampening out the hunting oscillations as explained in connection with Fig. 1 above and as shown graphically in Fig. 4.

Loading coils 4 and 5 are placed in the two branches of the antenna circuit to cut 35 down the value of circulating current in the path connecting the alternators to the antenna as obviously if this were a low impedance path the circulating current would flow through it in preference to the tie including inductance 31.

It will be noted that the usual single blocking condenser in the magnetic amplifier circuit has in this case been replaced by two, namely the condensers 12 and 14. 45 These two in series have the same capacity as the single condenser usually used for this purpose and in addition the condenser 12 serves to increase the circulating current between the machines. This utilization of 50 parts of the magnetic amplifier circuits as portions of the tie circuit is an important feature of the invention as it simplifies the circuit connections considerably and effects a large saving in the amount of apparatus 55 which would otherwise be necessary in connection with the keying circuit.

It is, therefore, apparent that the invention provides a very simple device for quickly damping out hunting oscillations in 60 the operation of alternators in parallel. A unique feature of the arrangement is that it is unnecessary to synchronize the alternators before closing the tie switch. This switch may be closed regardless of the phase 65 relation as the maximum current is less than

the load current of the alternators and no harm is done by thus connecting it. The resulting hunting is quickly damped for by an anti-hunting device.

Although the device has been explained in connection with a certain type of alternator it is obvious that this alternator is not an essential element of the system. The system can be used with alternators of different types. It is moreover obvious that 70 numerous keying and circuit arrangements will readily suggest themselves to those skilled in the art. For example, a single keying circuit could be used for both alternators. The system shown is given merely 75 by way of example and not in a limiting 80 sense.

Having described my invention what I claim is:

1. The combination of a plurality of alternators in parallel, a tie circuit between 85 said alternators, means in said tie circuit for damping hunting oscillations in said alternators and means operated by said alternators to control said damping means.

2. The combination of a plurality of alternators in parallel, a circuit connecting 90 said alternators, an impedance in said circuit, means for short circuiting said impedance and means responsive to change in direction of variation of phase angle between 95 said alternators to control said short circuiting means.

3. The combination of a plurality of alternators in parallel, a circuit connecting 100 said alternators, an impedance and means responsive to change in direction of variation of phase angle for inserting said impedance in said circuit when the phase angle between said alternators is decreasing.

4. The combination of a plurality of alternators in parallel, means responsive to 105 change in direction of variation of phase angle between said alternators for increasing the synchronizing torque between said alternators when the phase angle between them is increasing and for decreasing the synchronizing torque when the phase angle is decreasing, and means to control said first named means.

5. The combination of a plurality of alternators in parallel a circuit connecting said alternators, means for changing the impedance of said circuit when the direction of variation of the phase angle between said 110 alternators changes and means to control said first named means.

6. The combination of a plurality of alternators in parallel, means for changing the synchronizing torque between said alternators when the direction of variation of the phase angle between them is changing and means associated with the alternators for controlling said first named means.

7. The combination of a plurality of al- 115

ternators in parallel and means responsive to hunting oscillations in said alternators for increasing the synchronizing torque when the amplitude of hunting oscillations increases and for decreasing the synchronizing torque when the amplitude of hunting oscillations decreases.

8. The combination of a plurality of alternators in parallel and means responsive to hunting oscillations for developing large synchronizing torque as long as the phase angle between said alternators is increasing and means for reducing the synchronizing torque while the phase angle is decreasing.

9. The combination of two alternators connected in parallel, a circuit connecting said alternators, a variable impedance in said circuit, means for varying said impedance including a control circuit differentially connected to said alternators.

10. The combination of two alternators connected in parallel, a circuit connecting said alternators and including a variable impedance, means for varying said impedance including a control circuit differentially connected to said alternators, said control circuit including a rectifier and an impedance and means responsive to changing voltage across said impedance for varying said variable impedance.

11. The combination of two alternators connected in parallel, a circuit connecting said alternators including a variable impedance, a control circuit differentially connected to said alternators including a rectifier and an impedance, a condenser connected across said impedance and means responsive to the charging and discharging currents of said condenser for varying said variable impedance.

12. The combination of two alternators connected in parallel, a circuit connecting said alternators including a variable impedance, a control circuit differentially connected to said alternators including a rectifier and a resistance, a condenser connected across said resistance and means responsive to the charging and discharging currents of said condenser, for increasing the variable impedance when the condenser is discharging and decreasing the impedance when the condenser is charging.

13. The combination of two alternators connected in parallel, a circuit including an impedance connecting said alternators, a short circuiting device connected across said impedance, a control circuit differentially connected to said alternators including a rectifier and a resistance, a circuit connected across said resistance including a condenser and electromagnetic operating means for said short circuiting device responsive to the charging and discharging currents of said condenser.

14. The combination of two alternators

connected in parallel, a circuit connecting said alternators said circuit including a condenser and an inductance, a short circuiting device connected across said inductance, a control circuit differentially connected to said alternators, said control circuit including a rectifier and a resistance and a circuit connected across said resistance including a condenser and electromagnetic control means for said short circuiting device responsive to the charging and discharging currents of said condenser.

15. The combination of two alternators connected in parallel a circuit connecting said alternators including a condenser and an inductance, a short circuiting device for said inductance, a control circuit differentially connected to said alternators including a rectifier and a resistance, a condenser connected across said resistance and a polarized relay responsive to the charging and discharging currents of said condenser for operating said short circuiting device.

16. The combination of a plurality of alternators in parallel, a tie circuit connecting said alternators, means including an impedance in said tie circuit for damping hunting oscillations in said alternators, and means operated by said alternators to control said damping means.

17. The combination of a plurality of alternators in parallel, a circuit connecting said alternators, an impedance in said circuit, means for short circuiting said impedance, and means including a relay responsive to change in direction of variation of phase angle between said alternators to control said short circuiting means.

18. The combination of a plurality of alternators in parallel, a circuit connecting said alternators, an impedance associated with said circuit, and means responsive to change in direction of variation of phase angle between said alternators to insert said impedance in the connecting circuit.

19. The combination of a plurality of alternators in parallel, a circuit connecting said alternators, an impedance in said circuit, and a relay responsive to change in direction of variation of phase angle between said alternators adapted to short circuit said impedance.

20. A circuit arrangement comprising a plurality of alternators in parallel, a tie circuit between said alternators, means including an impedance in said tie circuit and a relay operatively associated therewith for damping out hunting oscillations in said alternators and means for increasing the synchronizing torque between said alternators.

21. In a circuit arrangement comprising a plurality of alternators in parallel, a tie circuit connecting said alternators an impedance in said tie circuit, a transformer as-

ciated with each of said alternators and adapted to be energized thereby, a circuit including a resistance and a rectifier connecting the secondaries of all of said transformers, a relay associated with said last named circuit and adapted to be controlled by differential current therein, and short circuiting means associated with said impedance and operated by said relay.

22. The combination of a plurality of alternators in parallel, a tie circuit connecting said alternators, an adjustable impedance in said tie circuit for damping hunting oscillations between said alternators, and a relay associated with said alternators to control said damping impedance.

23. The combination of a plurality of alternators in parallel, a tie circuit connecting said alternators, an adjustable impedance in said tie circuit for damping hunting oscillations in said alternators and a relay associated with said tie circuit and operated by said alternators to control said damping impedance.

24. The method of damping hunting oscillations between two alternators connected in parallel by a tie circuit of adjustable impedance which includes the step of combining a portion of the current generated by each of said alternators, rectifying the differential component of the combined current, and controlling the impedance of said tie circuit in accordance with variations in intensity of the rectified current.

25. In a circuit arrangement comprising a plurality of alternators in parallel and a load circuit energized thereby, a tie circuit connecting said alternators, an impedance in said tie circuit, means for short circuiting said impedance and means including a circuit operatively interposed between said alternators and said short circuiting means to control said short circuiting means.

JAMES L. FINCH.
